CLAIM

The ornamental design for an insulated container, as shown and described.

DESCRIPTION

FIG. 1 is a front perspective view of the insulated container with the lid in the closed position;

FIG. 2 is a front view thereof;

FIG. 3 is a rear view thereof;

FIG. 4 is left side view thereof;

FIG. 5 is a right side view thereof;

FIG. 6 is a top view thereof;

FIG. 7 is a bottom view thereof; and,

FIG. 8 is a front perspective view of the insulated container with the lid in the open position.

The broken lines depict portions of the insulated container that form no part of the claimed design.

1 Claim, 8 Drawing Sheets
